UNITED STATES PATENT OFFICE.

LAWRENCE E. ELLIS, OF NEW YORK, N. Y.

DESIGN FOR A TEXTILE FABRIC.

Application filed April 14, 1924. Serial No. 9,250. Term of patent 7 years.

To all whom it may concern:

Be it known that I, LAWRENCE E. ELLIS, a citizen of the United States, residing in New York, county of New York, State of New York, have invented a new, original, and ornamental Design for Textile Fabric, of which the following is a specification, reference being had to the accompanying drawing, forming part thereof.

The figure is a plan view of a textile fabric showing my new design.

I claim:

The ornamental design for a textile fabric substantially as shown.

LAWRENCE E. ELLIS.
